EARRING CLASP

Lipa Feingold, New York, N. Y.

Application January 29, 1944, Serial No. 520,244

4 Claims. (Cl. 63—14)

1

This invention relates to new and useful improvements in an ear ring clasp.

More particularly, the invention contemplates an improved ear ring clasp made from plastic or sheet metal and which is characterized by a harp-like resilient member for engaging against one side of the ear lobe and having its side arms directed downwards. It is proposed to provide an ornamental member for engaging against the other side of said ear lobe, and it is proposed that said ornamental member have a stem with a disc-like end axially pivotally mounted between the side arms of said harp-shaped member. The invention contemplates the provision of a leaf spring portion continuing from the central portion of said harp-like member and having ratchet teeth engaging complementary ratchet teeth on the edge of said disc-like end for holding the clasp closed on one's ear.

The invention also proposes a modified form in which a rigid slide is movable to various positions along said leaf spring portion for limiting flexing thereof.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a side elevational view of an ear ring clasp constructed in accordance with this invention and shown schematically applied to an ear.

Fig. 2 is a side elevational view looking in the direction of the line 2—2 of Fig. 1.

Fig. 3 is a fragmentary enlarged vertical sectional view taken on the line 3—3 of Fig. 2.

Fig. 4 is a side elevational view similar to Fig. 2 but illustrating a modified form of the invention.

Fig. 5 is a fragmentary enlarged vertical sectional view taken on the line 5—5 of Fig. 4.

Fig. 6 is a horizontal sectional view taken on the line 6—6 of Fig. 4.

In the form of the invention disclosed in Figs. 1—3 the ear ring clasp includes a harp-like resilient member 10 preferably formed from sheet metal and formed at the top of its inner side with a crescent shape plastic contact plate 10a. This member is adapted to engage against one side of an ear lobe, schematically illustrated in Fig. 1 by dot and dash lines 11. Said harp-like member 10 has side arms 12 which are formed

2

into lug portions 13. An ornamental member 15 is provided for engaging the other side of said ear lobe indicated by said lines 11. This ornamental member 15 has a jewel 16 or other ornamental piece mounted on its front face. The ornamental member 15 is also provided with a back stem 17 having a disc-like end 18 axially pivotally mounted between the lugs 13 with a pintle rivet 19.

10 A leaf spring portion 20 extends from the central portion of the material of the harp-like member 10. This leaf spring portion is provided with several ratchet teeth 21 engaging complementary ratchet teeth 22 formed on the edge 15 of said disc-like end 18. The extremity 23 of the leaf spring portion 20 extends past the disc-like end 18 so that it may be easily gripped by one's fingers and flexed outwards, as indicated by the dot and dash lines 20' in Fig. 1. In this 20 flexed position the ratchet teeth 21 disengage from the teeth 22 so that the ornamental member 15 is free and may pivot downwards free from the ear lobe 11, as indicated by the dot and dash lines 15'.

25 The operation of the clasp consists in placing it against the ear lobe so that the harp-like member 10 is to the back of the ear lobe and the ornamental member 15 is to the front. These members are pressed together so that the clasp 30 maintains itself on the ear lobe. The clasp may be removed by lifting up the end 23 of the leaf spring portion 20 so that the ornamental member 15 is released.

In Figs. 4—6 a modified form of the invention 35 is disclosed which is very similar to the first form, distinguishing merely in the fact that a rigid slide 25 is movably mounted and may be moved to various positions along the length of said leaf spring 20 for limiting the flexing of 40 said leaf spring. More specifically, the slide 25 is formed from two adjacent strips 26 and 27 which are secured together at several points by spot welds 28 or cement. These strips 26 and 27 engage opposite faces of the leaf spring 20 so 45 as to be movable along the length of the leaf spring. The ends of the strips 26 and 27 engage opposite faces of the side arms of the harp-like resilient member 10. One of the faces of said side arms is formed with serrations 29 engaged 50 by complementary serrations 30 upon the ends of the strip 26.

In other respects this form of the invention is similar to that previously shown and same reference numerals identify like parts in each of 55 the several views.

The rigid slide 25 may be shifted along the length of the leaf spring portion 20 and will be held in various positions by the serrations 29 and 30. In different positions, the slide 25 holds different lengths of the leaf spring 20 rigidly, so that it may not flex as easily. Consequently, if the slide 25 is nearer the base of the leaf spring 20 the free portion has greater flexibility than if the slide 25 is moved to a position nearer the free end thereof. The position of the rigid slide 25 determines the extent of the holding action between the serrations 21 and 22.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. An ear ring clasp, comprising a harp-like resilient member for engaging against one side of one's ear lobe and having its side arms directed downwards, an ornamental member for engaging against the other side of said ear-lobe and having a stem with a disc-like end axially pivotally mounted between the side arms of said harp-like member, and a leaf spring portion extending from the central portion of said harp-like member and having ratchet teeth engaging complementary ratchet teeth on the edge of said disc-like end, the free end of said leaf spring portion extending past said disc-like end so that it may be easily gripped and lifted.

2. An ear ring clasp, comprising a harp-like resilient member for engaging against one side of one's ear lobe and having its side arms directed downwards, an ornamental member for engaging against the other side of said ear-lobe and having a stem with a disc-like end axially pivotally mounted between the side arms of said harp-like member, and a leaf spring portion extending from the central portion of said harp-like member, having ratchet teeth engaging com-

plementary ratchet teeth on the edge of said disc-like end, and a rigid slide movable to various positions along said leaf spring portion for limiting flexing thereof.

3. An ear ring clasp, comprising a harp-like resilient member for engaging against one side of one's ear lobe and having its side arms directed downwards, an ornamental member for engaging against the other side of said ear-lobe and having a stem with a disc-like end axially pivotally mounted between the side arms of said harp-like member, and a leaf spring portion extending from the central portion of said harp-like member, having ratchet teeth engaging complementary ratchet teeth on the edge of said disc-like end, and a rigid slide movable to various positions along said leaf spring portion for limiting flexing thereof, comprising a pair of adjacent strips secured together at several points and slidably engaging opposite sides of said leaf spring portion, the ends of said strips engaging opposite faces of the side arms of said harp-like member.

4. An ear ring clasp, comprising a harp-like resilient member for engaging against one side of one's ear lobe and having its side arms directed downwards, an ornamental member for engaging against the other side of said ear-lobe and having a stem with a disc-like end axially pivotally mounted between the side arms of said harp-like member, and a leaf spring portion extending from the central portion of said harp-like member, having ratchet teeth engaging complementary ratchet teeth on the edge of said disc-like end, and a rigid slide movable to various positions along said leaf spring portion for limiting flexing thereof, comprising a pair of adjacent strips secured together at several points and slidably engaging opposite sides of said leaf spring portion, the ends of said strips engaging opposite faces of the side arms of said harp-like member, and serrations on one of said strips engaging complementary serrations upon said harp-like member.

LIPA FEINGOLD.
